Attorney

UNITED STATES PATENT OFFICE.

PAUL E. PAGE, OF MONTREAL, QUEBEC, CANADA.

WRENCH.

Application filed December 13, 1923. Serial No. 680,513.

To all whom it may concern:

Be it known that I, PAUL E. PAGE, a subject of the King of Great Britain, residing at Montreal, Province of Quebec, Canada, have invented certain new and useful Improvements in Wrenches; and I do hereby declare that the following is a full, clear, and exact description of the invention, such as will enable others skilled in the art to 10 which it appertains to make and use the same.

The present invention pertains to improvement on the wrench disclosed in the United States patent to Stephen R. Audibert, 1,081,193, December 9th, 1913.

The patented device comprises a shank, a ratchet bar slideable therealong, and a handle disposed beneath the lower end of the shank. The lower end of the ratchet bar 20 is formed with a single lug adapted for reception in a thread cut in the upper end of the handle. A jaw which is slideable along the shank may be moved into engagement with the article to be gripped, and the grip is secured by rotation of the handle whereby the ratchet bar is shifted upwardly, carrying with it the movable jaw by reason of a toothed engagement therewith. In order that the ratchet bar may be held in constant 30 engagement with the shank, a retaining collar is placed around these members at the lower ends thereof, while the upper end of the bar is formed with an arm receivable in a pocket cut in the shank.

One of the objects of the present invention is a wrench of this character constructed in such a manner that the special connecting means between the ratchet bar and the shank is rendered unnecessary. A further object 40 is to avoid wear and breaking of the lug and thread connection between the ratchet bar and handle, which is likely to occur in the use of the patented device.

Both these objects are fulfilled by providing the ratchet bar with a plurality of external threads at its lower end, in lieu of the inwardly projecting lug of the patented construction. The handle of the present invention is formed with internal threads 50 which surround the threads of the bar, as distinguished from the external thread of the patented wrench which receives the lug

projecting from the bar. In view of the fact that the connection between the ratchet bar and handle in the present construction exists over an elongated region, the ratchet bar is held in engagement with the shank without further provision. Moreover, the fact that a plurality of threads is used avoids wear and breakage which are due to concentrated strain in the patented construction.

Still another object of the invention is the provision of a novel separable jaw plate applicable to the wrench for forming an alligator jaw. In the Audibert patent, 1,103,927, July 21st, 1914, a plate is shown for application to the lower or movable jaw of the wrench. When the jaw is thus applied, the wrench must be held in reversed position or must be turned in the direction opposite to that in which a wrench is ordinarily turned. In the new construction, the separable plate is applied to the upper or stationary jaw so that the wrench may be turned in the usual manner.

The invention is fully disclosed in the following description and in the accompanying drawings in which:

Figure 1 is a side elevation of the wrench; Fig. 2 is a front elevation thereof; Fig. 3 is a longitudinal section; Fig. 4 is a perspective view of the ratchet; Fig. 5 is a section on the line 5—5 of Fig. 3; and Fig. 6 is a perspective view of the separable jaw plate.

Reference will now be had to these views by means of like characters which are employed to designate corresponding parts throughout.

The wrench, as shown particularly in Figure 3, comprises an elongated shank 1 at the upper end of which is formed an enlarged portion or ledge 2. Upon the latter member is carried a stationary jaw 3, preferably formed as an integral part of the shank.

Beneath the ledge 2 the shank is engaged along its edge by a ratchet bar 4. The major portion of the bar is formed with ratchet teeth 5, while the lower end has screw threads 6 cut therein. The bar is not fixed to the shank, but is free to slide therealong, as is pointed out below.

The shank and bar are surrounded by a slideable or movable jaw 7 formed with a toothed extension 8 adapted for cooperation with the teeth 5 of the bar 4. The aperture 9 of the movable jaw, within which the shank is contained, is slightly wider than the shank, as shown in Figure 3. The rear side of the jaw is formed with a recess 10 into which projects a spring 11 secured to the top of the jaw. This spring normally engages an edge of the shank and pulls the toothed portion 8 into engagement with the ratchet teeth 5. Because of this construction, the movable jaw may be swung in such a manner that the toothed portion 8 disengages the teeth 5 against the action of the spring 11, whereby this jaw may be adjusted to the article to which the wrench is to be applied.

The shank has at its lower end a substantially cylindrical stem 12, slightly flattened as at 13 to permit the ratchet bar 4 to slide therealong. A screw 14 is provided at the lower end of the stem and is adapted to receive a nut 15.

The lower portion of the shank, including the stem 12, is surrounded by a handle 16 formed with internal threads 17. The latter are adapted to engage the threads 6, as shown in Figure 3. It will be understood that the handle is applied before the nut 15 is screwed on the member 14. The intermediate portion of the shank is formed with a shoulder 18 which is engaged by a loose ring 19 surrounding the shank and ratchet bar. This ring completes the design of the wrench, and may be entirely omitted, as will be evident from the following description of operation.

In order to convert the wrench to a tool of the alligator jaw type, there is provided a separable jaw plate 20 having a flat top 21 and a notched bottom 22 which is disposed at an angle to the top. The top is formed with a rib 23 engageable in a recess 24 in the lower surface of the stationary jaw 3. To the sides of the plate is pivoted a yoke 25, the back 25' of which is receivable in a groove 26 cut in the top of the stationary jaw.

In use, the movable jaw 7 is tilted out of engagement with the ratchet bar in the manner already described. The two jaws are then clamped against the article to be gripped, and the lower jaw is released whereby the spring 11 brings the toothed extension 8 back into engagement with the ratchet teeth 5. The handle 16 is now turned in the direction which will retract the internal threads 17 thereof towards the lower end of the shank. The handle is incapable of longitudinal displacement with relation to the shank owing to the fact that it is bound between the nut 15 and ring 19. Consequently the rack must move, and is accord-

ingly shifted towards the upper jaw. The lower jaw 7 is carried therewith on account of its toothed engagement with the rack, whereby the grip upon the article which is clamped is tightened.

In the above-mentioned Patent 1,108,193, the lower end of the ratchet is held against the shank by means of a ring. The corresponding ring is not necessary in the present device, since sufficient engagement is obtained by reason of the reception of the plurality of threads 6 in the internal threads 17 of the handle. Moreover, the patented device requires a special construction for retaining the upper end of the ratchet in engagement with the shank in order to prevent displacement of the ratchet when the movable jaw is tilted. The plurality of threads 6 and 17 in the present instance are sufficient also to hold the upper end of the ratchet bar in proper position. The ring 19 does not correspond to the ring of the patented device, and may be eliminated, as already stated. It will be observed that the above described properties of the threads 6 and 17 are due to the fact that the ratchet bar is partially surrounded by the handle, as distinguished from the patented construction in which the ratchet bar overlies the thread of the handle.

In the patented wrench, connection between the handle and the ratchet bar is obtained by means of a single lug on the bar extending into a thread cut in the outer surface of the handle. This connection is rather weak, and is likely to break when the movable jaw is jammed against a nut or the like. Further difficulty in this construction is that the single thread becomes worn, whereupon the lug is liable to slip out. It will be noted that the improved construction comprises a plurality of threads on the ratchet bar engageable within a plurality of threads in the handle. The strain on these two members is therefore distributed, and the likelihood of wearing and breaking of threads is eliminated.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:

1. A wrench comprising a shank having a jaw at one end thereof, a rack-bar slidably engaging said shank and obstructed from said jaw, a movable jaw surrounding said shank and bar and having a toothed extension adapted for engagement with said bar, said bar having a threaded portion at its lower end, and a handle surrounding said

shank and threaded portion, said handle having internal threads for receiving the threaded portion of the bar.

2. A wrench comprising a shank having 5 a jaw at one end thereof, a rack-bar slidably engaging only one side of said shank throughout its entire length and obstructed from said jaw, a movable jaw surrounding said shank and bar and having a toothed

extension adapted for engagement with said 10 bar, said bar being threaded at its lower end, and a handle surrounding said shank and threads, said handle having internal threads for receiving the threads on the bar.

In witness whereof I have hereunto set 15 my hand.

PAUL E. PAGE.
